SMOKING PIPE

Nordal Mikelson, Sioux Falls, S. Dak., assignor of
forty-five per cent to R. E. Dickenson and W. J.
Dickenson, both of Sioux Falls, S. Dak.

Application March 2, 1943, Serial No. 477,727

4 Claims. (Cl. 131—202)

This invention relates to tobacco pipes, and the primary object thereof is to provide in a pipe bowl a simple and effective means of preventing accumulation of moisture in the lower part of the tobacco charge and in the smoke duct, and furthermore to provide such means without materially adding to the cost of the pipe and without unduly complicating its operation.

A well known disadvantage of tobacco pipes of the usual sort is that moisture from the burning tobacco, tar, and similar combustion products, being drawn from the burning tobacco at the top of the charge, are passed through the underlying tobacco and condense in the unburned tobacco, particularly at the bottom of the bowl and immediately adjacent the entrance of the smoke duct. This moisture interferes with proper burning of the lower part of the tobacco charge, and the condensed combustion products impart a harsh and disagreeable quality to the smoke produced by the tobacco containing them. The progressive increase in moisture content of the tobacco as combustion advances through the charge also results in condensation of increasing amounts of moisture and tar in the smoke duct, producing slugs that are drawn into the mouth of the smoker. The present invention overcomes these difficulties by providing passage for the smoke laterally from the combustion zone, to a large extent avoiding passage of the smoke through the lower part of the tobacco charge. Condensation of moisture and tar in the tobacco underlying the combustion zone is largely eliminated and the pipe bowl is thereby kept dry, permitting uniform combustion of the entire charge and production of a uniform quality of smoke.

In the accompanying drawing:

Fig. 1 is a side elevation of a pipe having a bowl arranged in accordance with this invention.

Fig. 2 is a plan view.

Fig. 3 is a sectional view on line 3—3 of Fig. 1.

Fig. 4 is an enlarged fragmentary longitudinal sectional view showing the novel portion of the pipe bowl.

Fig. 5 is a cross-sectional view of the smoke-conducting element of the assembly.

Describing the drawing in detail, the pipe comprises, as usual, a stem 6 and a bowl 7 provided with a wall 8 that encloses a combustion chamber 9. A smoke duct 10 communicates with the passage of the stem 6. In the usual form of pipe, a smoke duct corresponding to the duct 10 enters the bottom of the combustion chamber, so that

all products of combustion are drawn downwardly through the chamber and withdrawn at the bottom of the bowl. In the present bowl a smoke passage is extended alongside and parallel to the combustion chamber 9 and an elongate slot is provided for direct withdrawal of the smoke from the combustion zone. This may be accomplished, as illustrated, by means of a tubular element 11 arranged in a well 12 contained in the wall 8 at one side of and parallel to the combustion chamber, with which the well communicates by a gate 13. The smoke duct 10 communicates with a smoke passage 14 enclosed by the element 11 by way of a port 15.

15 Ingress to the smoke passage 14 enclosed by the element 11, for smoke from the combustion chamber 9, is provided by an elongate slot 16 extended axially of the element 11 and parallel to the direction of advance of the burning of the tobacco, which slot 16 is exposed to the interior of the combustion chamber 9 by the gate 13. The top end of the tubular element 11, being closed by a plug 17, it will be seen that suction applied to the smoke duct 10 will result in a current of air being drawn through the combustion chamber and through the passage 14 by way of the gate 13 and slot 16. When the combustion chamber is filled with tobacco and the latter is ignited, upon application of suction to the duct 10 smoke will be drawn laterally from the combustion zone and into the passage 14 of the tubular element 11, to a large extent avoiding passage through the tobacco underlying the zone of burning.

35 Since the burning tobacco presents a certain resistance to passage of air, it is necessary to satisfactory operation of the pipe to prevent passage of air directly to the passage 14 above the combustion zone. Such by-passing of the combustion zone is prevented by making the slot 16 sufficiently narrow to trap combustion products, including ash and carbon, from the combustion zone, which trapped products plug the slot progressively along its length as the combustion zone advances, thereby blocking the slot against free entrance of air above the burning tobacco. Sufficient resistance to air passage is set up by the trapped combustion products to insure passage through the combustion zone of air at a rate adequate to support combustion and effect flow of smoke to the passage 14 and the duct 10. When a charge of tobacco has been consumed, the trapped material plugging the slot 16 can be readily removed by blowing 50 sharply through the duct 10.

In order to facilitate the plugging of the slot 16, it is preferably V-shaped in cross-section, as shown in Fig. 5, with the wider side of the slot arranged externally of the element 11 and toward the combustion chamber 9. The inner, narrower side of the slot is wide enough to permit passage of smoke, but sufficiently narrow to trap fine ash and carbonized tobacco, and become plugged by such material.

Since a considerable part of the smoke entering the passage 14 by way of the slot 16 comes directly from the combustion zone, the smoke entering the passage 14 has hot and harsh qualities. To produce cooling and filtering effects similar to those of tobacco underlying the combustion zone in a standard pipe, the smoke passage 14 is filled with a body 18 of filtering material. Advantageously this material is tobacco, since by its use the normal flavor of the smoke is preserved, and the best qualities of a standard pipe are duplicated.

It has been proven by actual test that a pipe arranged in accordance with the foregoing disclosure avoids the disadvantages of the standard type of pipe bowl, and that a charge of tobacco burned therein will burn uniformly and completely without appreciable condensation of moisture in the lower part of the charge or the smoke duct, resulting in a completely "dry" pipe so far as delivery of harsh smoke and slugs of condensed moisture are concerned. The filtering material 18 may be replaced whenever necessary, the plug 17 being removable for the purpose.

I claim as my invention:

1. A tobacco pipe comprising a bowl having a combustion chamber and a well entirely separate and distinct from each other and substantially co-extensive in height and disposed in side to side relationship to each other, said bowl also having a slot substantially co-extensive in height with said combustion chamber and said well and affording constant communication throughout its height between said combustion chamber and said well, and a tube removably mounted in said well and substantially co-extensive in height therewith, said pipe including a stem having a smoke duct and

said tube being in communication adjacent to its lower end with said smoke duct, said tube having therein a slot substantially co-extensive in length therewith and aligned with the slot in said bowl, 5 said tube slot being sufficiently wide to afford ready passage for smoke from the combustion chamber into said tube and sufficiently narrow to trap combustion products from tobacco burnt in the combustion chamber so as to become progressively plugged by said products above the bottom of the combustion zone as said zone advances during burning of the tobacco.

2. A tobacco pipe as set forth in claim 1, in which the tube slot is substantially of V-shape in cross-section and is wider toward the combustion chamber than toward the smoke eduction passage and has a width toward the combustion chamber sufficient readily to receive combustion products from the zone of burning of tobacco in the chamber 10 and a width toward the smoke passage sufficiently narrow to trap such combustion products and become thereby plugged above the combustion zone as the latter advances.

3. A tobacco pipe as set forth in claim 1 in which the edges of the walls defining the elongated tube slot are spaced a relatively wide distance apart at the combustion chamber side of tube and in which the distance between the edges of the elongated spaced side walls of the tube slot away from the combustion chamber are substantially closer together than the first named edges of said walls.

4. A tobacco pipe including a bowl having a combustion chamber and a well separated by a division wall provided with a slot of substantially V-shape in cross-section affording communication therebetween, said slot being sufficiently wide to afford ready passage for smoke from the combustion chamber into said well and sufficiently narrow to trap combustion products from tobacco burnt in the combustion chamber so as to become progressively plugged throughout its length from top to the bottom thereof by said products above the bottom of the combustion zone as said zone advances during burning of the tobacco.

45 NORDAL MIKELSON.
